UNITED STATES PATENT OFFICE.

CHARLES MELROSE McCAMEY, OF DENVER, COLORADO, ASSIGNOR, BY DIRECT AND MESNE ASSIGNMENTS, TO JOHN EDWARD PAUL MEYER AND LATIMER D. GRAY, OF GOLDEN, COLORADO.

FURNACE-CLEANER.

SPECIFICATION forming part of Letters Patent No. 613,590, dated November 1, 1898.

Application filed December 21, 1897. Serial No. 662,870. (No model.)

To all whom it may concern:

Be it known that I, CHARLES MELROSE McCAMEY, of Denver, in the county of Arapahoe and State of Colorado, have invented a new and Improved Furnace-Cleaner, of which the following is a full, clear, and exact description.

The object of the invention is to provide a new and improved attachment for fire-boxes of steam-boilers, assay and other furnaces, oven-grates, &c., and arranged to permit of quickly and conveniently removing ashes, clinkers, and other solid matter from a grate directly into an ash-pit.

15 The invention consists of novel features and parts and combinations of the same, as will be fully described hereinafter and then pointed out in the claims.

Reference is to be had to the accompanying drawings, forming a part of this specification, in which similar characters of reference indicate corresponding parts in all the figures.

Figure 1 is a perspective front elevation of the improvement. Fig. 2 is a sectional plan view of the same on the line 2 2 of Fig. 1, and Fig. 3 is a sectional side elevation of the same on the line 3 3 of Fig. 1.

The setting for the furnace or other device on which the improvement is applied is provided with the usual inlet or fuel-charging doors A, leading to the grate B in the fire-box, the said grate being arranged to discharge the ashes directly into an ash-pit C in the usual manner.

35 In the dead-plate or bottom E of the inlet A and preferably close to the grate B is arranged an opening E', normally closed by a cover F, fitted to slide on the said dead-plate, the said cover being preferably provided at 40 its forward end with sidewise-extending lugs F', having a limited movement between stop-pins G, attached to or formed on the sides of the inlet A.

On the top of the cover F is preferably arranged a rib or boss F², adapted to be taken hold of by a suitable tool to push the cover F outward to uncover the opening E' or to push the said cover inward to close the said opening. When the cover F is in an outermost position, the opening E' is uncovered, and clinkers or other hard substances can be readily raked out by suitable tools into the

inlet or filling door to drop through the opening E' directly into the ash-pit C below. When the clinkers or the like have been removed, 55 the cover F is again pushed inward to its normal position to close the opening E'.

The under side of the dead-plate E is preferably formed with strengthening-ribs E² around the walls of the opening E' to give 60 the desired strength to the dead-plate.

In order to prevent an accumulation of ashes or small particles of fuel between the lugs F' and the stop-pins G, I provide the dead-plate E, adjacent to the stop-pins, with 65 apertures H, through which the ashes or small particles of fuel can readily pass to the ash-pit below, so as not to interfere with the free movement of the cover F.

Having thus described my invention, I 70 claim as new and desire to secure by Letters Patent—

1. A furnace having a rigid and immovable dead-plate located forward of the grate-bars and provided directly adjacent to the grate-bars with an opening through which clinkers may be discharged into the ash-pit, the dead-plate being also provided on its top face at points forward of the opening with stop-pins located two at each side of the dead-plate 80 and separated from each other, and a cover mounted to slide forward and back on the top face of the dead-plate and provided at each side near its front with a sidewise-extending lug, the lugs being respectively movable between the pairs of stop-pins whereby to limit the movement of the cover, and the cover being also provided on its top face with a rib running transversely to the dead-plate.

2. A furnace having an immovable and 90 rigid dead-plate located forward of the grate-bars and provided with an opening through which clinkers may be dropped into the ash-pit, and a cover commanding the opening and mounted to slide forward and back on the dead-plate and in a plane parallel with the plane thereof, the cover being supported by continual engagement with the top of the dead-plate.

CHARLES MELROSE McCAMEY.
